(57) **CLAIM**

The ornamental design for a handle body for surgical device, as shown and described.

DESCRIPTION

FIG. 1 is a rear, top, right side perspective view of a first embodiment of a handle body for surgical device, showing our new design;

FIG. 2 is a front view thereof, the rear view being a mirror image thereof;

FIG. 3 is a top view thereof;

FIG. 4 is a bottom view thereof;

FIG. 5 is a left side view thereof;

FIG. 6 is a right side view thereof;

FIG. 7 is an enlarged cross section view thereof, taken along the line 7-7 in FIG. 2;

FIG. 8 is a rear, top, right side perspective view of a second embodiment of a handle body for surgical device, showing our new design;

FIG. 9 is a front view thereof, the rear view being a mirror image thereof;

FIG. 10 is a top view thereof;

FIG. 11 is a bottom view thereof;

FIG. 12 is a left side view thereof;

FIG. 13 is a right side view thereof;

FIG. 14 is an enlarged cross section view thereof, taken along the line 14-14 in FIG. 9;

FIG. 15 is a rear, top, right side perspective view of a third embodiment of a handle body for surgical device, showing our new design;

FIG. 16 is a front view thereof, the rear view being a mirror image thereof;

FIG. 17 is a top view thereof;

FIG. 18 is a bottom view thereof;

FIG. 19 is a left side view thereof;

FIG. 20 is a right side view thereof; and,

FIG. 21 is an enlarged cross section view thereof, taken along the line 21-21 in FIG. 16.

The evenly spaced broken lines and dot-dash broken lines immediately adjacent the shaded areas represent the bounds of the claimed design while all other broken lines are directed to environment and are for illustrative purposes only; the broken lines form no part of the claimed design. The dot-dot-dash lines in the cross-section FIGS. 2, 9, and 16 views are used to identify the cross-section views and are for reference purposes only.
